COMBINED WATER WHEEL TOY AND LAWN SPRINKLER

John Louis Deets, Denver, Colo., assignor to Great Western Construction, Ltd., doing business as The Deets Manufacturing Co., Denver, Colo.

Filed Aug. 14, 1970, Ser. No. 24,488

Term of patent 14 years

Int. Cl. D23—01

U.S. Cl. D23—10

FIG. 1 is a perspective view of a combined water wheel toy and lawn sprinkler showing my new design.

FIG. 2 is an elevation view taken from one side thereof, the opposite side being a mirror image of the side shown.

FIG. 3 is a rear elevation view thereof, the ground stake being broken away for convenience of illustration.

FIG. 4 is a top plan view thereof.

I claim:

The ornamental design for a combined water wheel toy and lawn sprinkler, as shown.
